UNITED STATES PATENT OFFICE.

MORTIMER L. PACKER, OF COLUMBUS, OHIO, AND TURNER B. MESSICK, OF INDIANAPOLIS, INDIANA, ASSIGNORS TO THE OHIO STATE STOVE & MFG. CO., OF COLUMBUS, OHIO, A CORPORATION OF OHIO.

DESIGN FOR A HEATER.

Application filed March 26, 1923. Serial No. 5,604. Term of patent 7 years.

To all whom it may concern:

Be it known that we, MORTIMER L. PACKER and TURNER B. MESSICK, citizens of the United States, residing, respectively, at Columbus, in the county of Franklin and State of Ohio, and at Indianapolis, in the county of Marion and State of Indiana, have invented a new, original, and ornamental Design for Heaters, of which the following is a specification, reference being

had to the accompanying drawing, forming part thereof.

The figure is a front view of a heater, showing our new design.

We claim:

The ornamental design for a heater, as shown.

MORTIMER L. PACKER.
TURNER B. MESSICK.
